(57) **CLAIM**

The ornamental design for a bracket for parallel lengths of wiring, as shown and described.

DESCRIPTION

FIG. 1 is a front elevation view of a bracket for parallel lengths of wiring showing our new design;

FIG. 2 is a rear elevation view thereof of FIG. 1;

FIG. 3 is a top plan view thereof, the bottom plan view being a mirror image thereof;

FIG. 4 is a left side view thereof of FIG. 1;

FIG. 5 is a right side view thereof of FIG. 1; and,

FIG. 6 is a oblique view thereof of FIG. 1 showing the front, top, and right sides thereof.
